UNITED STATES PATENT OFFICE.

CHARLES PARTRIDGE CASSIDY, OF WASHINGTON, DISTRICT OF COLUMBIA.

STEM FOR PIPES OR CIGAR OR CIGARETTE HOLDERS.

SPECIFICATION forming part of Letters Patent No. 761,447, dated May 31, 1904.

Application filed February 18, 1904. Serial No. 194,274. (No model.)

To all whom it may concern:

Be it known that I, CHARLES PARTRIDGE CASSIDY, a citizen of the United States, residing at Washington, in the District of Columbia, have invented certain new and useful Improvements in Stems for Pipes or Cigar or Cigarette Holders; and I do declare the following to be a full, clear, and exact description of the invention, such as will enable others skilled in the art to which it appertains to make and use the same.

My invention relates to improvements in pipes and cigar and cigarette holders; and it consists in the construction, combination, and arrangement of devices hereinafter described and claimed.

The object of my invention is to effect improvements in the construction of the stem of a pipe or cigar or cigarette holder and to provide improved means to prevent the passage of nicotin to the user and to also prevent the passage of saliva to the tobacco.

In the accompanying drawings, Figure 1 is a longitudinal sectional view of a pipe exhibiting one form of my invention. Fig. 2 is a detail sectional view on a larger scale and showing the construction of the diaphragm. Fig. 3 is a longitudinal sectional view of a cigar-holder, the stem of which is constructed and provided in accordance with my invention.

The stem 1 of a pipe or cigar or cigarette holder is provided with separable sections 2 3, which are here shown as provided, respectively, with a threaded projection 4 and a threaded socket 5, whereby they may be screwed together to form a close joint. The said sections may be likewise joined together within the scope of my invention, and I do not desire to be understood as limiting myself in this particular. The said stem is chambered at the joint between the separable sections, as shown, and the said chamber is divided by a diaphragm 6 into a compartment 7 for nicotin and a compartment 8 for saliva. The diaphragm is removable from the chamber in the stem and is clamped between the stem-sections, as shown. Said diaphragm has at its center a tube 9, which projects into the com-

partment 8, its bore extending entirely through the tube, and the same is provided with lateral openings 10. The end of the tube in the compartment 8 is closed by a head or cap 11, which is here shown as screwed thereto, so that it may be removed to enable the bore of the tube to be readily cleansed. On the side of the diaphragm next to the chamber 7 is a hollow boss 12, which closes that end of the tube and is provided with perforations 13. Hence the diaphragm is provided with an air-passage, which enables the pipe or cigar or cigarette holder to be smoked. The nicotin is arrested by the diaphragm and held in the compartment 7, and the saliva from the mouth of the user collects in the compartment 8, as will be understood, so that it cannot reach the tobacco.

The cap 11 on the end of the tube of the diaphragm prevents the entrance of any saliva into the tube 9 that may be forcibly sent by the smoker into the stem, such saliva impinging against the cap and falling into the compartment 8.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of the invention.

Having thus described my invention, what I claim as new, and desire to secure by Letters Patent, is—

1. A pipe, cigar or cigarette holder having a chambered stem, a diaphragm in said chamber, dividing the same into a compartment for nicotin and a compartment for saliva, said diaphragm having a tube forming an air-passage therethrough, and extending into the saliva-compartment, said diaphragm being further provided, on the side next the nicotin-compartment, with a hollow boss which closes that end of the tube and is provided with perforations.
2. A pipe, cigar or cigarette holder having

- 5 a chambered stem, a diaphragm in said chamber, dividing the same into a compartment for nicotin and a compartment for saliva, said diaphragm having a tube forming an air-passage therethrough, extending into the saliva-compartment, opening laterally into said compartment and having a cap to prevent the passage of saliva therethrough and removable therefrom to enable the bore of said tube to be cleansed, said diaphragm being further provided, on the side next the nicotin-compartment, with a hollow boss which closes that end of the tube and is provided with perforations.
- 10 15 3. A pipe, cigar or cigarette holder having a chambered stem, a diaphragm in said chamber,

ber, dividing the same into a compartment for nicotin and a compartment for saliva, said diaphragm having a tube forming an air-passage therethrough, extending into the saliva-compartment, opening laterally into said compartment, and a cap on said tube to prevent the passage of saliva therethrough, and removable therefrom to enable the bore of said tube to be cleansed.
